(57) **CLAIM**

The ornamental design for a packing container, as shown and described.

DESCRIPTION

FIG. 1 is a perspective view of a packing container;
FIG. 2 is a front view thereof;
FIG. 3 is a rear view thereof;
FIG. 4 is a left side view thereof;
FIG. 5 is a right side view thereof;
FIG. 6 is a top plan view thereof; and,
FIG. 7 is a perspective view thereof when the packing container is closed.
The broken lines in the drawings showing illustrate the portions of the packing container that form no part of the claim.
